(57) **CLAIM**

The ornamental design for a static mixer, as shown and described.

DESCRIPTION

FIG. 1 illustrates a front perspective view of a static mixer having a plurality of curved arms circumferentially positioned around a central portion of the static mixer.

FIG. 2 illustrates a rear perspective view of the static mixer of FIG. 1.

FIG. 3 illustrates a front view of the static mixer of FIG. 1.

FIG. 4 illustrates a cross-sectional view of the static mixer of FIG. 1 along the cut depicted in FIG. 3.

FIG. 5 illustrates a rear view of the static mixer of FIG. 1; and,

FIG. 6 illustrates a side view of the static mixer of FIG. 1 having the rear of the static mixer on the left.
